UNITED STATES PATENT OFFICE.

SAMUEL RAYMOND, OF BOSTON, MASSACHUSETTS.

DOORLOCK.

Application filed April 24, 1925. Serial No. 25,486.

This invention relates to door locks and particularly to an attachment which is located on the inside of the door and is designed to have an interlocking engagement with the key and thus prevent it from either being rotated to unlock the door or from being pushed out from the lock by an unauthorized person on the outside of the door.

In order to give an understanding of the invention I have illustrated in the drawings some selected embodiments thereof which will now be described after which the novel features will be pointed out in the appended claims.

15 In the drawings, Fig. 1 is a front view of a door lock having my improvements applied thereto;

Fig. 2 is a vertical sectional view of the device shown in Fig. 1;

20 Fig. 3 is a view of the key;

Fig. 4 is a front view of a portion of the door showing a different embodiment of the invention;

Fig. 5 is a side view of Fig. 4 showing the 25 housing 25 in section.

In the drawings 1 indicates a portion of a door to which is secured the usual lock comprising a locking bolt 17 which is actuated by a key 5. 3 indicates the usual knob 30 by which the latch 18 is actuated and 2 represents the housing plate which is secured to the door and through which the knob 3 extends and which is provided with the key-hole slot 4. These parts are such as are 35 usually found in door locks and form no part of my present invention.

In locks of this type which are commonly used in houses and other buildings it sometimes happens that it is possible for a person 40 on the outside of the door to manipulate the key by the use of specially designed tools thereby to turn the key into position in which it may be pushed from the keyhole slot. Having thus removed the key an expert lock picker may pick the lock and gain 45 entrance to the room.

My invention is designed to prevent this from occurring and it comprises a key-locking member attached to the inside of the door 50 and adapted to have interlocking engagement with the key thereby to prevent it from being turned or pushed out of the lock. In the embodiment shown in Figs. 1 and 2 this key-locking member is a plate or arm 6 which is pivotally connected to the casing 2

of the door lock so that it can be swung upwardly into its inoperative position as shown in dotted lines Fig. 2 or downwardly in its operative position in which it has interlocking engagement with the key 5. 60

The locking plate 6 is shown as having a projection or protuberance 8 on its under face which is adapted to enter the opening 9 of the key when said locking member is in its operative position. When this projection occupies the opening 9 of the key as shown in full lines Figs 1 and 2 it will be impossible either to turn the key from the outside or to push the key out of the lock. 65

The connection between the member 6 and the housing 2 of the door lock is a yielding connection which will yieldingly hold the locking plate in either its inoperative or operative position. The locking plate is hingedly mounted on a wire 10 which extends transversely through the plate, said wire being bent laterally as shown at 11 and the lateral portion extending through openings 12 in the housing 2. Each end of the wire is then bent upwardly and then downwardly to form the loop 13. 70

Each loop has secured thereto one end of a spring 14, the other end of the spring being anchored to some fixed point such for instance as one of the screws 15 by which the housing 2 is secured to the door 1. The lateral bent portions 11 incline upwardly slightly so that the pull of the springs 14 tends to hold the inner edge of the plate 6 75 against the housing or face plate 2. 80

The inner edge of said plate 6 is formed with a nose or cam face 16 which is eccentric with the pivot pin 10. When the locking member 6 is turned upwardly from the full to the dotted line position Fig. 2 the nose 16 85 crowds against the face 7 of the housing 2 and forces the pivotal wire 11 away from said face plate slightly thus drawing the arms 11 through the openings 12, this movement being against the action of the springs 14. After the nose 16 passes the horizontal 90 line then the tendency of the spring 14 will be to assist in swinging the plate 6 into its inoperative position shown in dotted lines 95 Fig. 2. Similarly when the locking plate is 100 swung in its operative position the first part of the movement is against the action of the springs 14 and when the nose 16 passes the dead center then the springs tend to throw the locking plate downwardly into its opera- 105

110

tive position and also yieldingly maintain it in such position.

In order that the device herein shown may function properly it is necessary that the key should be left in the lock with the opening 9 in a horizontal plane so that the protuberance 8 may be carried into the opening when the plate is swung into its operative position.

10 In Figs. 4 and 5 I have illustrated a different embodiment of my invention wherein the key-locking member is entirely separate and distinct from the door lock or the housing 2. In this embodiment of the invention 15 the key-locking member is indicated at 19 and is shown as a U-shaped member having the ends of its arms 20 bent into hooks 21 which are adapted to hook into the opening 9 of the key. This key-locking member has 20 a stem 23 projecting therefrom which is connected to a spring 24 that is located in a housing 25, the latter having ears 26 by which it may be screwed to the inside of the door. When the key-locking device is not 25 in use the contracting action of the spring 24 will retain it in the dotted line position in which it is beneath the key. When in this position it does not interfere in any way with the operation of the key. The locking 30 of the key involves merely turning the key so that the opening 9 will be in a horizontal position and then raising the locking member and hooking the hooks 21 into said opening 9 of the key. This device will not only 35 prevent the key from being turned but will also prevent it from being pushed out of the keyhole.

The construction shown in Figs. 4 and 5 has the advantage that the key-locking device is separate from the door lock and may 40 be sold separately. This separate locking device can be quickly applied to any door regardless of the kind of lock with which the door is equipped.

45 The construction shown in Figs. 1 and 2 involves a special form of lock and housing.

I claim:

1. In a device of the class described, the combination with a door lock comprising a housing having a keyhole slot, a key-locking member, a pivotal connection therefor comprising a wire extending transversely through the key-locking member, said wire presenting laterally-extending arms which extend through the housing, and springs 55 within the housing connected to said arms.

2. In a device of the class described, the combination with a door lock comprising a housing having a keyhole slot, a key-locking member, a pivotal connection therefor comprising a wire extending transversely through the key-locking member, said wire presenting laterally-extending arms which extend through the housing, and springs 60 within the housing connected to said arms, the inner edge of said locking arm presenting a nose which co-operates with the spring 65 to hold the member yieldingly in either its operative or inoperative position.

3. In a device of the class described, the combination with a door lock, of a key for operating the same, said key having an opening in the end thereof, a U-shaped key-locking member, the ends of its arms being bent 70 backwardly to form hooks adapted to hook 75 into the opening of the key, and a spring acting on said locking member and yieldingly holding it in locking engagement with the key.

4. In a device of the class described, the combination with a door lock, of a key for operating the same, a U-shaped locking member, the ends of the arms of said member being bent backwardly to form hooks adapted 80 to hook into the opening of the key, a 85 housing secured to the door and a spring within the housing connected to said key-locking member.

In testimony whereof, I have signed my name to this specification.

SAMUEL RAYMOND.
